Company, Hartford, Conn., as trustee

Application February 8, 1947, Serial No. 727,426
In the Netherlands July 8, 1944

Section 1, Public Law 690, August 8, 1946
Patent expires July 8, 1964

6 Claims. (Cl. 315—261)

1

This invention relates to a circuit arrangement for a rectifier, which comprises one or more gas- or vapour-filled discharge tubes having an incandescent cathode and an auxiliary electrode, and which is furthermore equipped with a device, for instance a bi-metallic relay which permits the rectifier to be put into circuit in a retarded manner known per se.

In such circuit arrangements comprising non-controlled tubes it has hitherto been customary to make the bi-metallic relay operate a magnetic switch in the main current circuit (either at the primary side or at the secondary side), by the fact, that upon closing the bi-metallic contact the coil of the switch is energised. Such a device has the drawback that the construction of the switch is comparatively expensive especially below a definite value.

The present invention has for its object to provide a circuit arrangement of the kind referred to above, in which the magnetic switch is omitted and which is preferably designed in such a manner as to permit the use of rectifying tubes of the kind that are controllable by means of an auxiliary electrode, which need not be ignited anew by an auxiliary ignition device before every passage of the current.

According to the invention the ignition voltage on the auxiliary electrode in starting up the rectifier upon closing the contact of the bi-metallic relay is applied either indirectly or directly through this contact to the auxiliary electrode.

Tubes are preferably used which in the de-ionised state have a positive ignition characteristic and a de-ionisation time which amounts at least to a quarter cycle of the operating A. C. Well-known tubes of this kind are, for instance, rectifying tubes for a feed voltage of from 100 to several hundreds of volts having a gas-filling, an incandescent cathode and a so-called cathode-screen, which usually serves to reduce the risk of backfire in the tube. This screen acts as a grid in a relay tube in so far as the ignition voltage is high if the screen has the same potential as the cathode or is slightly negative with respect to the cathode, and if sufficient time has elapsed since the previous discharge in the tube. In this de-ionised state the tube has a so-called positive ignition characteristic i. e. that upon switching on, a positive current impulse has to be supplied to the screen to ignite the tube. If, however, care be taken, such as is feasible by a suitable choice of the dimensions and by a sufficient gas pressure, that the de-ionisation time at least amounts to a quarter cycle of the operating A. C.,

so that the tube is not yet de-ionised after a quarter cycle, then in cases where the currentless interval between two succeeding anode currents of one and the same tube amounts to $\frac{1}{4}$ cycle or more, the re-ignition voltage for the next passage of current will be low so that the auxiliary ignition need not take place for re-ignition in this and the next cycle. In practice, this state often occurs in charging accumulator batteries by means of a two-phase rectifying tube. If single-phase tubes are used it will be necessary to use a de-ionisation time of at least half a cycle.

In order that the invention may be clearly understood and readily carried into effect, it will now be described more fully with reference to the accompanying drawing, which represents, by way of example, two embodiments thereof. Each figure shows a circuit arrangement for two-phase rectification. For simplicity corresponding circuit parts bear the same reference numerals.

In Figure 1 the reference numeral 1 denotes the terminals of the A. C. mains to which is connected, through a switch 2, the primary 3 of a transformer 4. To the secondary 5 is connected in a manner known per se a double-phase rectifying tube 6 which together with the anodes 7 and 8 has a common grid 9 and the incandescent cathode 10. A load resistance 12 is connected in parallel with the D. C. network between the connecting terminals 11.

The control voltage for the tube 6 is supplied through the intermediary of a valve 13, for instance a high-vacuum tube and a bi-metallic relay 14. To this end the anodes 15 and 16 of tube 13 are respectively connected to one or both halves 17 and 18 of the secondary 5 of the transformer 4 and the incandescent cathode 19, through the heating member 20 and the resistance 21 to the incandescent cathode 10 and consequently also to the positive terminal of the direct current network 11. The movable part 22 of the bi-metal relay is likewise connected to the incandescent cathode 19 of tube 13 and the fixed contact 23 through a limiting resistance 24 to the grid 9 of tube 6. The potential of the grid 9 relatively to the cathode 10 is determined by the resistance 25.

The operation of the device described, which has for its object to switch on the rectifying tube 6 in a retarded manner in conjunction with possible damaging of the incandescent cathode, is as follows:

After closing the switch 2 the incandescent cathodes 10 and 19 are heated. When the latter has become sufficiently hot a current passes, in

accordance with the polarity, from one of the secondary windings 17 and 18 through one of the anodes 15 and 16, the heating member 20, the resistance 21 and the resistance 12 (which may also be the load itself if it has already been put into circuit) to the mid-point tapping of the secondary of transformer 4. After a certain delay the bi-metal 22 engages the contact 23 and on the auxiliary electrode 9 of the tube 6 is set up such a positive voltage relatively to the incandescent cathode 10 as to permit ignition of the tube 6 in one of the anode circuits. At this moment a current is still flowing through the heating member 20 and the resistance 21. The desired current distribution over the two branches can be obtained by a judicious choice of the resistance 21 and 24.

The tube 6 having been ignited, the D. C. network is fed and the voltage of the anodes 7 and 8 falls off to the arc voltage of the tube. Due to this current through the tube 13 falls off to such a degree that the bi-metal cools and the contact is opened at 23. The auxiliary current through this contact is then interrupted, it is true, but the tube 6 keeps operating, since its de-ionisation time exceeds a quarter cycle of the alternating feed current, as a result of which the re-ignition is low in the second and next half cycle after switching on by means of the switch 2, so that an auxiliary ignition, as obtained upon switching on through the tube 13, is superfluous.

Thus it is feasible to switch on in a retarded manner and to feed, upon switching on, the D. C. network so long as the switch 2 is closed, without the tube 6 need be ignited by a separate auxiliary voltage in each half cycle. After cooling down the bi-metal 22 is ready again to bring about the desired delay upon switching on again by means of the switch 2.

The circuit arrangement shown in Fig. 2 is a variant of Fig. 1, in which the additional load resistance 12 shown in Fig. 1 is omitted, or the network load need not be put into circuit, before starting up the rectifier.

Upon closing the switch 2 the heating member 20 is traversed by current from an auxiliary winding 26 of transformer 4, which current passes through the switch 27 and the contact at 28 of a relay 29. Upon closure of the contact 23 an auxiliary current may pass from the auxiliary winding 30 of transformer 4 through the tube 13, the contact at 28, contact 23 and coil 31 of the relay, resistance 24, auxiliary electrode 9 and incandescent cathode 10 to the midpoint tapping of the auxiliary winding 30. Owing to this the tube 6 is capable of igniting as soon as the load circuit is closed. The relay now interrupts the contact at 28 as a result of which the switch arm 27 engages the contact at 33 in the position indicated in dotted lines, through which contact the auxiliary current keeps flowing. At the same time, however, the circuit comprising the bi-metal is interrupted, so that the bi-metal is allowed to cool down and is consequently ready again to bring about the desired ignition delay of the tube 6 upon switching it on anew by means of the switch 2. The circuit remains open so long as the switch 2 is closed, for in this state the coil 31 is steadily energised, even if the tube 6 be extinguished by interruption of the load circuit.

What I claim is:

1. A power supply system comprising a gaseous rectifier tube having a control electrode, a time-delay relay having a normally open switch and

an electrically energized element for actuating said switch, a source of alternating voltage, rectifier means to derive an ignition voltage from said source, means to apply said ignition voltage through said switch onto said electrode, means to derive an energizing current for said element from said source, means to impress for rectification an alternating voltage from said source onto said tube and simultaneously to supply said energizing current to said element whereby following an interval determined by the characteristic of said relay said switch is actuated by the energized element and said ignition voltage is applied to said electrode to fire said tube, and means responsive to the change in internal impedance upon the firing of said tube for reducing the supply of energizing current to said element to a level causing said switch to reopen.

2. A power supply system comprising a gaseous rectifier tube having a control electrode, a thermostatic relay having a normally open bimetallic switch and an electrical heating element for actuating said switch, a source of alternating voltage, rectifier means to derive an ignition voltage from said source, means to apply said ignition voltage through said switch onto said electrode, means to derive an energizing current for said element from said source, means to impress for rectification an alternating voltage from said source onto said tube and simultaneously to supply said energizing current to said heating element whereby following an interval determined by the thermal characteristic of said relay said switch is actuated by the energized element and said ignition voltage is applied to said electrode to fire said tube, and means responsive to the change in internal impedance upon the firing of said tube for reducing the supply of energizing current to said element to a level causing said switch to reopen.

3. A power supply system comprising a gaseous rectifier tube having a control electrode, a thermostatic relay having a normally open bimetallic switch and an electrical heating element for actuating said switch, a diode rectifier device, a resistance, said device being connected serially with said heating element and said resistance in the order named in parallel with said tube, the junction of said heating element and said device being connected through said switch to said electrode, a source of alternating voltage, means to impress for rectification an alternating voltage from said source across said tube whereby after a time interval determined by the thermal characteristic of said relay the ignition voltage developed across said resistance is applied through said switch to said electrode to fire said tube, the firing of said tube decreasing the voltage thereacross and effecting a reduction in the current flow through said heating element thereby causing said switch to reopen.

4. A power supply system comprising a voltage transformer having a primary and a center-tapped secondary, a gaseous rectifier tube having a cathode, a pair of anodes and a control electrode, said anodes being connected to opposite ends of said secondary, a rectifier device having a cathode and a pair of anodes connected to opposite ends of said secondary, a thermostatic relay having a normally open bimetallic switch and an electrical heating element for actuating said switch, a first resistance, the cathode of said device being connected through said heating element and said first resistance to the cathode of said tube, a second resistance connected be-

5

tween said control electrode and the junction of said element and said first resistance through said switch, a third resistance connected between the centertap of said secondary and the cathode of said tube, and means to apply an alternating voltage to said primary.

5. A power supply system comprising a voltage transformer having a primary and a centertapped secondary, a gaseous rectifier tube having a cathode, a pair of anodes and a control electrode, said anodes being connected to opposite ends of said secondary, said tube having a positive ignition characteristic in the deionized state and a deionization time amounting to at least a quarter cycle of an applied alternating voltage, a rectifier device having a cathode and a pair of anodes connected to opposite ends of said secondary, a thermostatic relay having a normally open bimetallic switch and an electrical heating element for actuating said switch, a first resistance, the cathode of said device being connected through said heating element and said first resistance to the cathode of said tube, a second resistance connected between said control electrode and the junction of said element and said first resistance through said switch, a third resistance connected between the centertap of said secondary and the cathode of said tube, and means to apply an alternating voltage to said primary.

6. A power supply system for a load, said system comprising a voltage transformer having a primary, first and second centertapped secondaries and an auxiliary winding, a gaseous rectifier tube having a cathode, a pair of anodes and a control electrode, said anodes being connected to

opposite ends of said first secondary, a rectifier device having a cathode and a pair of anodes connected to opposite ends of said second secondary, a thermostatic relay having a normally open bimetallic switch and a heating element for actuating said switch, an electromagnetic relay having a normally closed armature switch and a coil for actuating said switch, said heating element being connected through said armature switch across said auxiliary winding, a first resistance, the cathode of said device being connected through said armature switch, said bimetallic switch and said first resistance to the cathode of said tube, the junction of said resistance and said bimetallic switch being connected through said coil to said control electrode, the centertap of said second secondary being connected to the cathode of said tube, and means to connect the load between the centertap of said first secondary and the cathode of said tube.
